M. J. SKUBÉ

FIREPLACE DAMPER

Filed Oct. 19, 1925

Patented Apr. 20, 1926.

1,581,403

UNITED STATES PATENT OFFICE.

MATHIAS J. SKUBÉ, OF SEATTLE, WASHINGTON.

FIREPLACE DAMPER.

Application filed October 19, 1925. Serial No. 63,416.

To all whom it may concern:

Be it known that I, MATHIAS J. SKUBÉ, a citizen of the United States, residing at Seattle, in the county of King and State 5 of Washington, have invented certain new and useful Improvements in Fireplace Dampers; and I do declare the following to be a full, clear, and exact description of the invention, such as will enable others skilled 10 in the art to which it appertains to make and use the same.

The invention relates to improvements in dampers of the type used in the throats of fireplaces to not only control the draft, but 15 to prevent descent of cold air from the chimney when the fireplace is not in use.

One object of the invention is to provide a new and improved frame carrying a pivoted damper plate and constructed to effectively support the crown at the open 20 front of the fireplace, with the lower edge of such crown spaced downwardly from the major portion of the frame.

Another aim is to provide new and improved means for adjusting the pivoted damper plate and holding it in any of a plurality of different open positions.

With the foregoing in view, the invention resides in the novel subject matter herein- 30 after described and claimed, the description being supplemented by the accompanying drawing.

Figure 1 is a vertical transverse sectional view through the improved damper installed 35 in the throat of a fireplace.

Figure 2 is a top plan view of the damper separate from the fireplace.

Figure 3 is an end elevation.

Figure 4 is a vertical longitudinal sec- 40 tional view as indicated by line 4-4 of Fig. 2.

Figure 5 is a perspective view of the adjusting lever for the pivoted damper plate.

In the drawing above briefly described, 45 the numeral 6 designates a horizontally disposed, elongated frame, preferably formed in one piece of cast metal, although in some instances, it could be otherwise constructed.

This frame includes a forwardly inclined 50 back plate 7 and a pair of vertically dis- 45 posed end plates 8 joined to and projecting forwardly from the ends of said back plate, the front portions of said end plates having downward projections 9. A rearwardly inclined front plate 10 is joined to the front

ends of the end plates 8 and to their downward projections 9, said front plate having end portions 11 which project laterally beyond the end walls 8, these laterally projecting end portions preferably having their outer edges disposed in downwardly diverging relation, as disclosed in Fig. 2. The upper edges of the back and front plates 7 and 10 are disposed substantially at the 65 same elevation, but said front plate projects downwardly to a plane considerably below the back plate 7 and is provided with an integral longitudinal flange, projecting forwardly and disposed in said plane, said flange being indicated by the character 12. The lower edge of the back plate 7 is provided with an integral outwardly projecting flange 13 which is relatively narrow when 70 compared to the flange 12, and other flanges 14 project outwardly from the lower edges of the end plates 8, throughout the major portions of these plates. The front end portions of the flanges 14 however, extend horizontally across the outer sides of the 75 downward projections 9 and are integrally joined to the upper portions of the laterally projecting plate ends 11.

The flanges 13 and 14 assist in properly 80 supporting and anchoring the frame 6 in the throat of a fire place, as will be clear from Fig. 1, and the flange 12 then effectively supports the crown C at the open front of the fire place, with the lower edge of such crown much lower than the major 85 portion of the frame 6. Thus, this frame is not only obscured from view, but I am enabled to use a relatively wide front plate 10 which will effectively direct smoke rear- 90 wardly and upwardly instead of having any 95 tendency to permit it to escape into the room.

I have above stated that the edges of the projecting plate portions 11 diverge downwardly and attention may here be directed to the fact that the ends of the flange 12 diverge forwardly so that said flange is provided with acute front corners 12^a which may be embedded in the masonry at the vertical sides of the fireplace, so that the flange and the front portion of the frame will be well supported, to in turn carry the weight of the fireplace crown and the masonry thereover.

A damper plate 15 is provided to close 110 the upper portion of the frame 6, said plate being preferably transversely arched, as

shown. This plate is pivoted at its front edge with the latter extending along the upper edge of the front plate 10, and while any desired pivotal mounting means could be employed, I preferably provide the plate 15 with integral trunnions 16, one of these trunnions being received in an opening in one of the end plates 8, while the other is similarly received in a notch 17 in the other 10 of said end plates. This construction permits quick and easy insertion or removal of the damper plate and also expedites manufacture. When the plate 15 is closed, its rear portion lies upon the back wall 7 and 15 it will be seen that its ends abut the inner side of the end plates 8.

Novel adjusting means is provided for the damper plate 15. The lower side of this plate is provided at one end with a plurality 20 of ribs 18 which extend longitudinally of said plate. Fulcrumed at 19 to the inner side of one of the end plates 8, under the ribbed end of the damper plate 15, is a lever 20 having an upper end 21 to engage the 25 ribs 18. By swinging this lever in one direction, opening of the plate 15 is effected, whereas movement of the lever in the other direction permits closing of the damper plate, and by engagement of the lever end 21 with the ribs 18, it will be seen that 30 said damper plate will be effectively held in any open position to which it is adjusted. The fulcrum 19 of the lever 20 is preferably 35 formed with a lateral lug 22 normally preventing slipping of the lever 20 therefrom, said lug however being receivable in a

groove 23 formed in the lever, when the latter is turned to an abnormal position. Thus, the lever may be readily removed or applied and a detail is produced which is 40 of manufacturing advantage.

The device is simple and inexpensive, yet is efficient and very desirable, and when the damper plate is open, with the fireplace in operation, any descending cold air will 45 be deflected by the shape of the device and cannot descend into the room. Of course, when the fireplace is not in use, the damper plate is entirely closed and it then effectively prevents entrance of cold air. 50

On account of the excellent results obtainable from the details disclosed, they are preferably followed, but within the scope of the invention as claimed, slight variations 55 may be made.

I claim:

In a fireplace damper; a frame, a gravity-closed damper plate pivotally mounted to close the upper portion of said frame, the lower side of said damper plate having at 60 one end a plurality of parallel ribs which extend longitudinally of said plate, and a lever fulcrumed at the inner side of said frame for swinging movement in a vertical plane transverse to said plate, said lever 65 acting to raise said plate and having an upper end for engagement with said ribs to prop said plate in different open positions.

In testimony whereof I have hereunto affixed my signature.

MATHIAS J. SKUBÉ.
